UNITED STATES PATENT OFFICE.

JOSEPH H. WHILT, OF HOQUIAM, WASHINGTON, ASSIGNOR TO LAMB MACHINE COMPANY, OF HOQUIAM, WASHINGTON.

PAWL-AND-RATCHET MECHANISM.

1,165,218.

Specification of Letters Patent. Patented Dec. 21, 1915.

Application filed September 17, 1915. Serial No. 51,246.

To all whom it may concern:

Be it known that I, JOSEPH H. WHILT, a citizen of the United States, residing at Hoquiam, in the county of Chehalis and State of Washington, have invented certain new and useful Improvements in Pawl-and-Ratchet Mechanism, of which the following is a specification, reference being had therein to the accompanying drawing.

10 This invention relates to certain new and useful improvements in a pawl and ratchet mechanism for rotating a shaft intermittently.

Another object of my invention is to provide a pawl and ratchet mechanism in which a two-piece casing is employed for inclosing the same so as to thoroughly protect the pawl and ratchet mechanism from dirt and dust.

20 Another object of my invention is to provide a ratchet mechanism in which lost motion is practically eliminated, the construction of the same being such that the gear and ratchet wheel can be packed with grease 25 so as to eliminate noise and to keep the mechanism thoroughly lubricated at all times.

Another and further object of my invention is to provide a ratchet mechanism in 30 which is arranged a ratchet wheel having a hub provided with a gear which meshes with a pair of oppositely disposed pinions, which in turn meshes with the internal gear of the casing employed for inclosing the same so 35 that when motion is transmitted to the casing by an operating member it will be transmitted through the pawl and ratchet mechanism, and gear to the central hub which is keyed on the shaft thereby enabling a fine 40 adjustment to be obtained in order to impart the proper throw of the shaft which is being rotated.

Other and further objects and advantages of the invention will be hereinafter set forth 45 and the novel features thereof defined by the appended claims.

In the drawings: Figure 1 is a perspective view of my improved construction of ratchet mechanism showing the same in position 50 upon the shaft, Fig. 2 is an elevation of one of the sections of the casing showing the ratchet wheel and pawl in position therein, Fig. 3 is a section taken on line 3—3 of Fig. 4, and Fig. 4 is a vertical section taken 55 through the pawl and ratchet mechanism to

show the same keyed on the end of the shaft to be rotated.

Like numerals of reference refer to like parts in the several figures of the drawings.

In carrying out my invention, I employ 60 a two-piece casing preferably cylindrical in shape, the inner section 1 being provided with a lip in which is pivotally mounted a spring actuated dog 2, upon a pin 3, and normally held in engagement with a ratchet 65 wheel 4, which is provided with a hub portion 5, the bore of which is arranged in horizontal alinement with an apertured boss 6 formed centrally in the casing 1. The hub portion 5 is provided with a gear portion 7, 70 adapted to mesh with a pair of oppositely disposed pinions 8 and 9, carried by stud pins 10 and 11, mounted in the oppositely disposed arms of a hub member 12, and upon which the hub portion of the ratchet 75 wheel is mounted to revolve. The hub member 12 is provided with oppositely disposed notches at each end forming key slots for securing the same upon a shaft 13 to be rotated, said hub member being secured in position upon the shaft by a nut 14, as clearly shown, employed for holding the keys in position within the notches thereof, and it will be noticed that I have formed the hub member with notches at both ends so that 80 the same can be secured in position upon a shaft to be rotated at either end of the shaft in either direction. The other section of the two-piece casing of the pawl and ratchet mechanism comprises a section 15 conforming in shape to the section 1, and having an apertured boss in alinement with the apertured boss of the other section, said section being provided with a lip 16, adapted to register with the lip formed on the section 90 1 and in which the opposite end of the pivot pin 3 of the dog is secured, as clearly shown in Fig. 4.

The lips are provided with registering apertures adjacent each end through which 100 pivot pins are adapted to extend for connecting the casing to an operating rod 17, as shown in Fig. 1, employed for imparting an oscillatory motion to the casing. The section 15 of the casing is provided with an internal gear portion 18 adapted to mesh with the pinions 8 and 9 carried by the central hub member so as to equalize the motion imparted to the ratchet mechanism whereby 105 the same can be adjusted to a nicety so as 110

to operate the shaft through the medium of the pawl and ratchet mechanism as any motion imparted to the casing in one direction is transferred to the pawl and ratchet mechanism and internal gear portion of the casing to the central hub member fixed upon the shaft to be driven.

The sections of the casing are provided with apertured ears 19 through which a bolt 20 is adapted to extend for firmly fastening the sections together, and it will be seen by this construction the sections can be readily secured together or separated so as to reach the interior of the mechanism. When in use, the casing is packed with grease so as to thoroughly lubricate the mechanism therein and to reduce the wear and noise when in operation.

It will be seen that when the pawl and ratchet mechanism is secured on the end of a shaft, as shown in Fig. 1, when the operating rod is given a pull, the casing will be oscillated carrying with it the ratchet wheel and through the medium of the gears of the ratchet wheel and gears of the casing, motion is imparted to the hub member through the medium of the pinions so as to cause the hub member to oscillate the shaft to which it is secured.

From the foregoing description, it will be seen that I have provided a pawl and ratchet mechanism which is capable of being readily attached to a shaft to be intermittently rotated in either direction, composed of a central hub member revolubly mounted within the casing and provided with oppositely disposed pinions meshing with the internal gear of the casing and the gear carried by a ratchet wheel whereby any motion which is transmitted to the outside can be closely gaged and practically any adjustment made up to at least one one-hundredth part of an inch.

What is claimed is:

- 45 1. In a pawl and ratchet mechanism, a shaft, a hub member fixed on said shaft provided with oppositely disposed arms, pinions carried by said arms, a ratchet wheel loosely mounted upon said hub member provided with a gear meshing with said pinions, a casing inclosing said pinions, hub member and ratchet wheel and a gear carried by said casing meshing with said pinions.
- 50 2. In a pawl and ratchet mechanism, a shaft, a hub member fixed on said shaft, a casing loosely mounted on said hub member, a ratchet wheel loosely mounted upon said hub member provided with a gear, oppositely disposed arms formed on said hub member, pinions carried by said arms meshing with said gear, a pawl carried by said casing coöperating with said ratchet wheel and a gear formed on said casing coöperating with said pinions.

3. In a pawl and ratchet mechanism, the combination with a shaft to be rotated, of a hub member fixed on said shaft, a ratchet wheel loosely mounted upon said hub member provided with a gear, pinions carried by said hub member coöperating with said gear, a casing inclosing said hub member and ratchet wheel, a pawl carried by said casing coöperating with said ratchet wheel, and a gear carried by said casing coöperating with said pinions.

4. A pawl and ratchet mechanism, comprising a two-piece casing having registering lips, a pivoted spring actuated dog mounted in said lip, a ratchet wheel arranged within said casing coöperating with said dog, a gear formed centrally on said ratchet wheel, a hub member having a bearing for said ratchet wheel, arms extending outwardly from said hub member carrying pinions meshing with the gear of said ratchet wheel, and a gear carried by one of the sections of said casing meshing with said pinions.

5. In a pawl and ratchet mechanism, the combination with a shaft to be rotated, of a hub member having notches at its ends arranged upon said shaft, keys carried by said shaft extending into said notches, said hub member being provided with oppositely disposed arms carrying bearing pins, pinions loosely mounted upon said bearing pins, a ratchet wheel loosely mounted upon said hub member having a central gear meshing with said pinions, a casing inclosing said hub member and ratchet wheel and mounted to oscillate upon said hub member, a dog member carried by one of the sections of said casing coöperating with said ratchet wheel and a gear formed internally on the other section meshing with said pinions.

6. The combination with a shaft to be rotated, of a hub member keyed to said shaft provided with oppositely disposed laterally projecting arms carrying pinions, a ratchet wheel loosely mounted upon said hub member having a gear meshing with said pinions, a casing surrounding said hub member having a gear meshing with said pinions, and a pivoted dog arranged within said casing coöperating with said ratchet wheel.

7. The combination of a shaft to be rotated, of a hub member fixed on said shaft provided with oppositely disposed arms carrying pinions, a casing mounted to oscillate upon said hub member, a dog carried by said casing, a ratchet wheel revolubly mounted upon said hub member engaged by said dog, a gear carried by said ratchet wheel meshing with said pinions, a gear carried by said casing meshing with said pinions, said shaft being locked to the casing by said dog by the motion of the casing in one direction and unlocked therefrom by

the motion of the casing in the opposite direction.

8. A pawl and ratchet mechanism, comprising a casing mounted to oscillate, a hub member fixed to a shaft upon which said casing is mounted, said hub member being provided with oppositely disposed arms, a ratchet wheel revolubly mounted upon said hub member having a central gear, pinions carried by said arm meshing with said gear, an internal gear formed in said casing meshing with said pinions, and a pivoted dog carried by said casing and coöperating with said ratchet wheel.

15 9. In a pawl and ratchet mechanism, the combination with a shaft to be rotated, of a member fixed on said shaft, pinions carried by said member, a ratchet wheel rota-

table on said shaft, a gear carried by said ratchet wheel meshing with said pinions, a 20 member oscillatable on said shaft having a gear meshing with said pinions, a dog carried by said oscillatable member coöperating with said ratchet wheel, said shaft being locked to said oscillatable member by said 25 dog by the movement of said oscillatable member in one direction and unlocked therefrom by the movement of the oscillatable member in the opposite direction.

In testimony whereof I hereunto affix my 30 signature in the presence of two witnesses.

JOSEPH H. WHILT.
